JOHN A. HEYL, OF BOSTON, MASSACHUSETTS.

Letters Patent No. 63,794, dated April 16, 1867.

IMPROVED RAILWAY SWITCH.

The Schedule referred to in these Letters Patent and making part of the same.

TO ALL PERSONS TO WHOM THESE PRESENTS SHALL COME:

Be it known that I, JOHN A. HEYL, of Boston in the county of Suffolk, and State of Massachusetts, have invented an improved Railway Switch operative mechanism; and I do hereby declare the same to be fully described in the following specification and represented in the accompanying drawings, of which—

Figure 1 is a top view; and

Figure 2 a longitudinal section of the main and turn-out rails and switch of a railway as provided with my invention for operating the switch by means of a carriage while running from the main toward the turn-out rails, or from the latter toward the former.

In the drawings, A A' are the two rails composing the switch, they, at or near one end of each, being hinged or jointed to the two main-track rails B B', so as to be capable of being moved horizontally on centres a a, from the continuation main-track rails B² B³ to the sideling or turn-out rails C C', or from the latter to the former, as circumstances may require. The two switch-rails A A' are connected by a bar, D, jointed to both of them near their free extremities, the same being for preserving their parallelism as well as for another purpose. Between the switch-rails is a bent lever, E, whose fulcrum, b, is at the middle of the lever, and extends upward from the road bed, or some suitable part of the superstructure of the track. This lever is connected to each of the switch-rails by one of two toggles, F F', each of which is jointed or hinged both to the switch-rail and the lever, the whole being so that by a movement of the lever in one direction on its fulcrum the switch-rails may be moved into line with the main-track rails; also so that by a movement of the lever in an opposite direction on such fulcrum the switch-rails may be moved into line with the rails of the sideling or turn-out.

For effecting such movements of the lever I employ mechanism which may be thus described: In the drawings, G is a horizontal shaft, provided with two cranks, e e', at its ends, and two bell-cranks, d d', arranged between the terminal cranks. This shaft is supported in bearings, e e e, arranged between the main-track rails B B', in manner as represented in the drawings. When one of the bell-cranks is horizontal the other is inclined to the horizon, that is to say, the plane of the two bell-cranks is at an acute angle with each other, the vertex of which is at the axis of the shaft G, each of the terminal cranks being extended downward from the shaft, and disposed at or about at a right angle with the next adjacent bell-crank. Two connecting-rods, H H', lead from the wrists of the terminal cranks to the lever E, to which they are jointed on opposite sides of its fulcrum, as shown in fig. 1. Furthermore, two inclined bars or planes, I I', arranged so as to turn on a horizontal rod, e', are applied to the wrists of the two bell-cranks, each of such wrists being extended through a slot, f, made in the bar. There is to be on the axle of the locomotive or railway carriage, or on some other proper part therof, a wheel, provided with a means of sliding it laterally, so that when the locomotive or carriage is on the track-rails B B' the wheel may be moved into a position to roll on either of the inclined bars or planes I I' while the carriage is in the act of passing over them; the object of such wheels being to depress the inclined plane so as to cause the switch to be moved from alignment with those of the sideling or turn-out, or the reverse, according to the inclined plane run over and depressed by such wheel. The drawings exhibit the inclined planes and their cranked shaft as arranged so as to actuate the switch while the locomotive or railway carriage may be running on the track-rails B B'; but a set of the inclined planes, cranked shaft, and connecting-rods, as described, may be disposed between the rails B² and C', the connecting-rods being jointed to the lever E. In this case the switch may be operated when the carriage may be on either the tracks B², B³, or C C', and running toward the switch, such operation of the switch being to bring it into alignment with the track on which the carriage may be running.

From the above it will be seen that the movement of the switch may be effected by the engine before it may reach it, and thus the usual expense of the employment of a switch-tender may be avoided. Each arm of the lever E, with its toggle, answers as a pair of toggles to operate with the connection-bar D in moving the switch-rails, and holding them in position when in alignment with either the main or sideling tracks.

Having thus described my invention, I wish it to be understood that I am aware that the relative position of a switch with a main track or turn-out, or sideling track, has been changed by the action of mechanism attached to a carriage as well as by devices applied to the track, such being as exhibited in the United States Patent No. 8,531, dated November 18, 1851. I am also aware of the devices for such purposes as shown in the rejected

applications of Morton, Buck and Andrews, filed in the United States Patent Office August 17, 1850; and John C. Smith, filed in the United States Patent Office June 13, 1857; all of which differ materially from my invention, for in neither of them do we find the switch-rails connected with a horizontal lever by toggles, such as shown at F F' in fig. 1 of the above-mentioned drawings, each of such toggles not only serving to aid in the movement of the switch, but, with the curved lever E, to operate to lock the switch in position. Furthermore, my arrangement and application of the cranked shaft G with the levers I I' is different from anything exhibited in the said patent or rejected applications, for in my invention the bell and terminal cranks are all on one shaft, to which the two levers I I' and the connecting-rods H H' are applied. The movement of one lever causes a counter-movement of the other through the agency of the shaft and bell-cranks. My invention is simple and more efficient than others, as heretofore mentioned.

I claim the arrangement of the bars I I', the cranked shaft G, the connecting-rods H H', the lever E, the toggles F F', and the connecting-bar D, the whole being applied to the switch, and so as to aid in operating it, in manner and under circumstances substantially as hereinbefore explained.

JOHN A. HEYL.
